FIG. 2.

Owen H Spencer
Inventor

UNITED STATES PATENT OFFICE

OWEN H. SPENCER, OF INDIANAPOLIS, INDIANA

CYLINDER PORT CONTROL

Application filed June 11, 1929. Serial No. 369,996.

This invention relates to means for introducing air or gaseous charge into the cylinders of an internal combustion engine, and one feature of the invention is the provision of a chamber independently of the exhaust and intake tappet controls and preferably therebetween.

A further feature of the invention is in so constructing the chamber that any lubricant carried into the chamber with the air will be separated therefrom and collected in the chamber.

A further feature of the invention is the provision of means for conveying the collected lubricant to the valve tappets and operating parts therefor and eventually returning the lubricant to the crank case of the engine.

A further feature of the invention is the provision of an air controlling valve for regulating the admission of air to the cylinders of the engine.

A further feature of the invention is the provision of means for operating said valve for closing the same in timed relation with the valve tappets, the operating means being separate from the means employed for operating the intake and exhaust valve tappets.

Other objects and advantages will be hereinafter more fully set forth and pointed out in the accompanying specification.

In the accompanying drawings which are made a part of this application,

Figure 1 is a vertical transverse sectional view thru an internal combustion engine and the air chamber associated therewith.

Figure 2 is an enlarged detail sectional view of the air chamber, showing the intake and exhaust valve tappets associated therewith.

Referring to the drawings in which similar reference numerals designate corresponding parts thruout the several views, the numeral 1 designates the cylinder of an engine of the internal combustion four-stroke cycle type, in which is slidably mounted a piston 2, said cylinder having an intake valve 3 in the top portion thereof and an air inlet port 4 and an exhaust port 4^a in the bottom portion thereof.

In order to convey air to the inlet port 4

for scavenging the cylinder 1, a chamber 5 is constructed on the face of the cylinder 1, preferably between the tappets 6 and 7, employed for operating the usual form of intake and exhaust valves associated with each cylinder. Charge for the chamber 5 is preferably conveyed thru the crank case 8 of the engine in any suitable manner, any suitable form of conduit 9 extending from said crank case to the receiving port 10 of the chamber 5. By conveying the air thru the crank case 8 to the chamber 5, such air is more or less impregnated with lubricant or oil particles, and by placing the receiving port 10 adjacent the upper end of the chamber 5, the major portion of the lubricant will separate from the air and be collected in the lower portion of the chamber, from whence it is conveyed thru bores 11 onto the tappets 6 and 7, from whence it descends by gravity onto the cams 12 and 13, used for operating the tappets 6 and 7, respectively, and thence descends into the crank case 8.

The chamber 5 is provided with a partition 14, which is located between the inlet port 4 and the receiving port 10, said partition having a valve receiving opening 15 therethru for the passage of air from the chamber proper to the inlet port 4.

Cooperating with the opening 15 is a valve 16, which has a sliding fit with the opening 15, the wall of the opening being somewhat elongated so that the valve 16 may have some vertical movement without uncovering the opening 15 so that said valve will open only incident to the explosion stroke of the piston. The valve 16 is attached to a tappet 17, the upper end of the tappet having a pintle 18 slidably mounted in a socket 19 at the upper end of the chamber 5, while the lower portion thereof extends thru a guide 20 and into engagement with a cam 21 on a shaft 22, the cams 12 and 13 being preferably attached to the same shaft. The cam 21 acts to elevate the tappet 17 and valve 16, while the valve and tappet are moved downwardly by means of a spring 23 between the top end of the chamber 5 and the valve 16. If desired, a bore 24 may be formed lengthwise of the pintle 18 to permit air to escape from the socket 100.

19 as the pintle is forced into the same, or permit air to enter the socket to prevent vacuum therein as the pintle moves outwardly in the socket.

5 The guide 20 is provided with an enlarged base 25, which not only forms a support for the guide, but forms the bottom wall of the chamber 5, the diameter of the base being such that the valve 16 may be entered or re-
10 moved thru the opening in which the base fits. The peripheral edge of the base 25 is provided with a flange 26, which fits a recess 27 in the lower edge of the chamber 5 so that when the cylinder is clamped to the engine
15 base in the usual manner, the guide 20 will be locked in position within the chamber 5. In addition to forming a closure for the lower end of the chamber 5, the base 25 forms a closure for the opening 28 in the top portion
20 of the crank case 8, thru which the tappet 17 projects. The base 25 may be provided with one or more ports 29 thru which the lubricant within the chamber 5 may descend onto the tappet 17, and thence by gravity to the
25 cam 21 and into the crank case 8.

While the description and drawings illustrate in a general way certain instrumentalities which may be employed in carrying the invention into effect, it is evident that many
30 modifications may be made in the various details without departing from the scope of the appended claims, it being understood that the invention is not restricted to the particular examples herein described.

35 I claim as my invention:

1. The combination with a cylinder of an engine having valve controlled inlet and exhaust ports in its outer end, a piston controlled exhaust adjacent its inner end, and
40 tappets for operating said valves, of an air chamber independent of said tappets and having an air inlet port opposite the lower exhaust port, a partition in said chamber, a valve seat in said partition, a valve adapted to slide through said seat for controlling the passage of air through the air chamber and air inlet port cooperating therewith, a tappet carrying said valve, means for operating said latter tappet in timed relation
45 with the first mentioned tappets, and means for conveying air to said chamber.

2. The combination with the cylinder of an engine, an exhaust and an intake port adjacent the outer end thereof and an exhaust
55 port adjacent its inner end, and a crank case having an opening therethrough, of an air chamber positioned over said opening in the crank case, means for introducing air from the chamber into said cylinder at a point
60 opposite said inner exhaust port, a removable base for said chamber adapted to rest over and cover the opening in the crank case, a hollow guide on said base, a tappet pro-
65 jecting through said guide and opening, a

valve for controlling the admission of air to said cylinder, and a cam in said crank case for moving said valve to closed position.

In testimony whereof, I have hereunto set my hand on this the 31st day of May, 1929,
A. D.

OWEN H. SPENCER.
